Thomas Carrick

INVENTOR

BY *Victor J. Evans*

ATTORNEY

UNITED STATES PATENT OFFICE.

THOMAS CARRICK, OF ALLENWOOD, NEW JERSEY.

FIRE-CURTAIN-OPERATING DEVICE.

Application filed May 25, 1927. Serial No. 194,222.

This invention relates to stage curtain operating devices, and its general object is to provide a releasing apparatus for lowering a gravity drop fire curtain, that is entirely automatic in its operation of lowering the curtain in the event of fire or intense heat capable of causing fire in the building in which the curtain and apparatus is installed, regardless of the remoteness with respect to the 10 curtain, of the fire in the building.

A further object of the invention is to provide a stage fire curtain releasing apparatus, that is not only automatic in its operation in releasing and dropping the curtain, but prevents the sudden drop of the curtain and retards the speed thereof after it has reached a safe distance, and fully stops the movement thereof when it is dropped to a position to completely close the stage from the remaining 20 portion of the building.

A still further object of the invention is to provide a stage fire curtain releasing means of the character as above set forth, that also sounds an alarm simultaneously with the 25 dropping of the curtain.

This invention also consists in certain other features of construction and in the combination and arrangement of the several parts, to be hereinafter fully described, illustrated in 30 the accompanying drawings and specifically pointed out in the appended claims.

In describing my invention in detail, reference will be had to the accompanying drawings wherein like characters denote like or 35 corresponding parts throughout the several views, and in which:

Figure 1 is a diagrammatic view of the curtain releasing apparatus which forms the subject matter of the present invention.

Figure 2 is a front view of the trip mechanism therefor.

Figure 3 is a view taken at right angles to Figure 3 and illustrating the trip mechanism after the same has been operated.

Figure 4 is a similar view with the trip mechanism in operative position.

Figure 5 is a partial sectional view of one of the fusible elements of my invention.

Referring to the drawings in detail the letter A broadly indicates a stage provided with

the usual decorative curtains as shown, and normally arranged above the stage and capable of closing the stage opening thereof is the usual fire curtain B which is adapted to be dropped to operative position through the 55 instrumentality of the apparatus which forms the subject matter of the present invention.

The curtain B has fixed to its upper edge a strip 1 which has arranged in its length and rising therefrom a plurality of eyes 2 arranged in pairs and are adapted to receive one of the ends of cables 3 which are trained about sheave wheels 4 journaled to a beam 5 which rests upon eye beams of the building as shown. The beam 5 has also secured there- 60 to eyes 6 for receiving one of the ends of chains 7 which have their opposite ends secured in eyes 8 secured to the strip 1 between the pairs of eyes 2 and arranged in parallelism therewith. It will be obvious that the 65 chains 7 are adapted to limit the downward movement of the curtain B.

The cables 3 by virtue of the fact of being secured to the eyes 2 are also arranged in pairs, and one cable of each pair is fixed to a cable 9 which is trained over a sheave wheel 10 and has fixed to its lower end a weight 11. The remaining cables of each pair are disposed in an opposed direction with respect to the cables 3 which are fixed to the cable 9, and these remaining cables are secured to a cable 12 which is likewise trained over a sheave wheel 13 arranged in parallelism with the sheave wheel 10.

The cable 12 has its lower end secured to 85 a frame 13 through the medium of an apertured ear 14 which is pivotally secured to the frame, and arranged in said frame for movement therewith is a tank 15 adapted to contain liquid which is supplied thereto by a hose 90 16 having connection with a supply pipe 17 which is in communication with any suitable source of supply. Depending from the tank 15 and arranged in communication therewith is a drain pipe 18 which has disposed therein 95 a valve 19 controlled by a lever 20 in a manner which will be presently apparent. The drain pipe 18 is mounted for slidble movement in a waste pipe 21 so that regardless of the position of the tank 15, the drain pipe 18 will at 100

all times be in communication with the waste pipe 21.

Arranged in juxtaposition with respect to the tank 15, there is a supporting plate 22 which has disposed thereon the tripping mechanism of my apparatus. Secured to and arranged in superposed relation on said supporting plate 22 are angle brackets 23 and 24. The horizontal portions of said angle brackets are disposed in parallelism and are provided with openings through which pass rods 25 which are mounted for slidable movement therein. The lower end of each rod is formed with an eye 26 and surrounding each rod is a coil spring which has one end convolution engaging the horizontal portion of the bracket 24 and the opposite convolution of the springs is fixed to its rod midway its ends as best shown in Figure 2 of the drawings. Extending forwardly from adjacent the upper end of the supporting plate 22 and arranged upon opposite sides of the angle bracket 23 is one of a pair of apertured ears 27 which receive a shaft 28 for rotation therein. Secured to the shaft 28 between the ears 27 is an elongated member 29 which has arranged midway its ends and extending forwardly therefrom is a releasing finger 30. The rods 25 are held in their lower position and against the tension of their springs as shown in Figure 2 of the drawings by the elongated member 29, and said elongated member is held in its rod holding position through the medium of the engagement of the finger 30 with the free end of a lever 31 which has its opposite end pivotally secured between spaced apertured ears 32 extending forwardly from the supporting plate 22 as best shown in Figures 3 and 4 of the drawings. The lever 31 is curved from its pivot point in order to provide a hook like portion 33 which accommodates a link 34 having secured thereto a weight 35. The weight 35 has also secured thereto one end of a chain 36 which has its opposite end fixed to the lever 20 of the valve 19 as best shown in Figure 1 of the drawings.

The fusible members each include a housing 37 and these housings may or may not be counter-sunk in the walls and ceilings of a building within which my apparatus is installed. These fusible elements may be arranged at any desired place in the building either adjacent to or remote from the stage 55 and curtain B. While I have shown only four fusible elements and means to be operated thereby, it will be obvious that any number may be employed with the apparatus constructed accordingly. Arranged in the housing of each fusible member is a fusible element 38 which is tapered from its ends toward its center so as to provide a restricted central portion 39 of suitable thickness to resist ordinary temperatures, but heat from fire and heat capable of producing fire will

melt the fusible element at its central portion. Each of the housings is provided with a reticulated cover 40 so as to allow the free passage of heat but otherwise protects the fusible element which has secured to one end 70 a link for fixing the same within the housing and fixed to the opposite end of said element is a wire 41 leading to the tripping mechanism and is secured to the eye 26 of one of the rods 25 as clearly shown in Figure 1 of the drawings. Of course, the wires are suitably trained in their passage from their fusible elements to their rods. Secured to the supporting plate 22 below the ears 32 and in a manner to be arranged in the path of the rounded portion 42 of the arm 31 is a pair of spaced contact plates 43 being in electrical connection with a source of energy and a signal which in the present instance is shown as being an electric bell 44.

Rising from the frame 13 is a rod 44 which has secured to its upper end a piston 45, and arranged in the path of the piston 45 is a cylinder 46 having a flared lower end 47 which acts to guide the piston 45 therein. The cylinder 46 is formed with a plurality of openings 48 at its upper end so as to allow escape of air as will be apparent. Arranged in the path of the lever 20 is a roller 49 adapted to engage said lever for closing the valve 19.

From the above description and disclosure of the drawings, it will be obvious that I have provided a curtain releasing means which is entirely automatic and positive in operation, and in the event heat from a fire should melt anyone of the fusible elements 38, the wire 41 thereof will be released which will likewise cause the spring of the particular rod having fixed thereto the released wire, to move said rod upwardly and carry the elongated member 29 accordingly so as to release the arm 31 and the weight 35 from the latter. The weight will operate the lever 20 to open the valve which will let the liquid escape from the tank 15. When the tank 15 loses sufficient liquid so as to overbalanced by the weight of the curtain B, it will be apparent that the curtain will begin to drop by gravity and raise the tank accordingly. When the tank has reached a sufficient height 115 so that the piston 45 is arranged in the cylinder 46, the movement of the curtain will be retarded and approximately at the same time the lever 20 will be actuated by the roller 49 to prevent further escape of liquid from the tank 15, with the result, that the curtain will be stopped gradually and thereby prevent breakage or disarrangement of any of the hangings thereof, or apparatus for operating the same, and of course the curtain 125 finally stops when the curtain completely closes the stage opening A.

It is thought from the foregoing description that the advantages and novel features of my invention will be readily apparent.

I desire it to be understood that I may make changes in the construction and in the combination and arrangement of the several parts, provided that such changes fall within 5 the scope of the appended claims.

What I claim is:

1. A holding and lowering controlling device of the character described comprising a liquid tank, a plurality of fusible elements, 10 a tripping mechanism controlled by anyone of the fusible elements, a drain pipe for said liquid container, a valve in said drain pipe for releasing the liquid from said container, and means controlled by the tripping mechanism for operating said valve.

2. Means for holding a curtain in raised position and controlling the lowering thereof, comprising a liquid tank having connection with a gravitational curtain and to move upwardly and thereby permit downward movement of a curtain, a weight having connection with said curtain, said tank adapted to have liquid therein of sufficient weight to retain the curtain in raised position with the aid of the weight first mentioned, fusible elements, a tripping mechanism controlled by anyone of said fusible elements, a drain pipe in communication with said tank, a valve in said drain pipe, means controlled by said tripping mechanism for operating said valve to open position for releasing the liquid from said tank to allow the curtain to lower under the action of gravity, and means for retarding the lowering of said curtain.

3. Means for holding a curtain in raised position and controlling the lowering thereof, comprising a weight having connection with said curtain, a frame, a liquid tank arranged in said frame, means of connection between said frame and a gravitational curtain whereby said tank when filled with liquid retains said curtain in raised position with the aid of said weight, fusible elements, a tripping mechanism controlled by anyone of said fusible elements, an alarm operated by said tripping mechanism, means controlled by said tripping mechanism for releasing liquid from said tank to allow the curtain to drop by gravity and to simultaneously sound the alarm, and means for retarding the downward movement of said curtain.

4. Means for holding a gravitational curtain in raised position and controlling the lowering thereof, comprising a weight having connection with said curtain, a frame, flexible elements between said frame and curtain, a tank arranged in said frame and adapted to hold liquid of sufficient weight to retain said curtain in elevated position with aid of the weight first mentioned, a tripping mechanism, fusible elements controlling said tripping mechanism for retaining the same in set position, an arm included in said tripping mechanism, valve means for releasing the liquid from said tank, a weight carried by

said arm and being adapted to open said valve means to allow the curtain to drop, means in the path of said valve means to close the same, and means for retarding the downward movement of said curtain, a cylinder included in the retarding means, a piston carried by the frame and adapted to be received in said cylinder.

5. The combination with a vertical movable liquid tank, of a valve for normally retaining liquid in said tank, a weight for opening said valve and bringing about discharge of liquid from the tank, means normally and detachably holding said weight against gravitational movement, and thermostatic means for effecting the release of the weight when said thermostatic means is acted upon by heat.

6. The combination with a vertical movable liquid tank, of a valve for normally retaining the liquid in said tank, a weight for opening said valve for releasing liquid from the tank, a pivoted lever normally supporting said weight, pivoted means for holding said pivoted lever in weight supporting position, spring pressed rods mounted for slidable movement and adapted to operate said pivoted means, thermostatic elements, a wire for each element and rod and being connected thereto, whereby when any one of the elements is acted upon by heat it will release the rod connected thereto for moving said pivoted means from said pivoted lever to allow the latter to drop said weight to open the valve.

7. The combination with a vertical movable liquid tank, of a valve for normally retaining the liquid in said tank, a weight opening said valve to release liquid from the tank, a pivoted lever normally supporting said weight, pivoted means for holding said pivoted lever in weight supporting position, a supporting plate, angle brackets secured in spaced relation on said supporting plate, spring pressed rods mounted for slidable movement in said angle brackets and terminating at one end in eyes, said rods being adapted to operate said pivoted means, thermostatic elements, wires secured in the eyes and connected to the thermostatic elements, whereby when any one of the elements is acted upon by heat it will release the rod connected thereto for moving said pivoted means from said pivoted lever to allow the latter to drop said weight to open the valve.

8. The combination with a vertical movable liquid tank, of a valve for normally retaining liquid in said tank, a weight for opening said valve to release liquid from said tank, a pivoted lever normally supporting said weight, pivoted means for holding said pivoted lever in weight supporting position, an alarm, spaced contact plates arranged in the path of said pivoted lever and in electrical connection with said alarm, spring pressed

rods mounted for slidable movement and adapted to operate said pivoted means, thermostatic elements, a wire for each element and rod and being connected thereto, whereby when any one of the thermostatic elements is acted upon by heat it will release the rod connected thereto for moving said pivoted

means from said pivoted lever to allow the latter to drop said weight and to bridge the contacts so as to simultaneously open the valve 10 and sound the alarm.

In testimony whereof I affix my signature.

THOMAS CARRICK.
